UNITED STATES PATENT OFFICE.

JOHN W. FRYER, OF ST. CHARLES, IOWA.

GATE-OPERATING MEANS.

1,181,129.

Specification of Letters Patent. Patented May 2, 1916.

Application filed January 26, 1912. Serial No. 673,616.

To all whom it may concern:

Be it known that I, JOHN W. FRYER, a citizen of the United States, residing at St. Charles, in the county of Madison and State of Iowa, have invented new and useful Improvements in Gate-Operating Means, of which the following is a specification.

The invention relates to swinging gates, and more particularly to the class of gate openers.

The primary object of the invention is the provision of a gate opener in which the gate proper may be swung from closed to opened position, or vice versa, at either side thereof, the gate, when closed being locked, and is automatically released for the opening thereof.

Another object of the invention is the provision of a gate opener in which the weight of the gate is relieved from the levers which are manually actuated for the opening and closing of the said gate, thereby requiring little exertion on the part of a person, when operating the opener.

A further object of the invention is the provision of a gate opener, which is simple in construction, strong, durable, reliable and efficient in operation, as well as being easily and conveniently manipulated, and that may be manufactured at a minimum expense.

With these and other objects in view, the invention consists in the construction, combination and arrangement of parts, as will be hereinafter more fully described, illustrated in the accompanying drawings, and pointed out in the claims hereunto appended.

In the drawings: Figure 1 is a side elevation of a gate and opener therefor constructed in accordance with the invention. Fig. 2 is a top plan view. Fig. 3 is a sectional view. Fig. 4 is a fragmentary side elevation of the gate, with one of the latch posts removed, thus showing in detail the manner of locking the said gate. Fig. 5 is a perspective view of the latch member removed from the gate.

Similar reference characters indicate corresponding parts throughout the several views of the drawings.

Referring to the drawings by numerals, 5 designates spaced vertical gate posts, and 6 the vertical latch posts, the same being arranged on opposite sides of a roadway, respectively, in the usual well-known manner, and between said gate posts 5 is ar-

ranged a vertically swinging gate 7 which may be of any desirable construction, and made from any suitable material, the gate being supported upon a pivot 8 carried at 60 one end thereof and journaled in bearings 9 secured to the gate posts 5. The pivoted end of the gate 7 has thereon a segmental-shaped weight or ballast 10 adapted to serve as a counterweight. This weight 10 is a 65 true semi-circle and has its straight edges secured to the rear straight edge of the gate 7. This semi-circular weight is arranged concentrically of the pivot 8 so that when the latch member is disengaged and the lever 16 operated, the gate may swing on pivot 8, thereby causing the counterweight to assist the gate in its pivotal movement, the gate swinging a half a revolution so as to come to rest upon the ground and assume a 70 horizontal open position. In this way the gate will swing back and forth to a horizontal closed and a horizontal open position, thereby preventing the wind from having any effect in making the open gate revert 75 to its closed position.

Carried by the opposite end of the gate is a latch, comprising a spring bar 11, one end of which is fixed to the gate, while its opposite end is inturned to form a handle 85 or finger engaging extremity 12, the bar being bent intermediate its ends to provide a latch shoulder 13 adapted for locking engagement with a keeper pin 14 fixed transversely in the latch posts 6, so that on swinging the gate to closed position the shoulder 13 will engage the pin 14, thereby locking the said gate closed.

The gate is moved and simultaneously the latch member released by means of a gate 95 opener, comprising hand operated rocking levers 15, the same pivoted at 16 upon the upper ends of supporting posts 17 mounted in the ground at opposite sides of the gate 7, contiguous to the gate posts 5, the levers 15 100 being provided at their inner ends with eye members 18, to which are loosely connected pull links 19, the latter being also loosely connected to laterally projecting headed studs 20 formed on a swinging yoke 21 105 which is connected to the gate 7 by means of a pivot 22, so that upon pulling downwardly upon the free ends of either of the levers 15, the gate may be swung from closed to opened position, or vice versa.

Connected with the yoke 21 is a pull or latch releasing rod 23, the same being con-

nected to the spring bar 11 forming the latch member. Thus, when the yoke 21 is moved, upon operating the levers 15, the rod 23 will be pulled upon, retracting the spring bar 11, and disengaging its shoulder 13 from the keeper pin 14, thereby unlocking the gate prior to the swinging of the same to open position.

What is claimed is:

10. In combination a pair of spaced apart gate posts, a pair of uprights, a rod connecting said posts, a gate, a semi-circular weight secured with its straight edge against the straight edge of said gate, said gate being fulcrumed upon said rod in such a way as to make said semi-circular weight swing concentrically to said rod, upper diagonally

disposed portions formed upon said uprights, said diagonal portions converging toward said post, a pair of levers having elongated slots through which said diagonal portions project, pins pivotally connecting said levers upon said portions, crank arms carried by said gate at opposite sides, and rod connections from said cranks to said levers, whereby said gate may swing completely around said rod a half a revolution, when said levers are turned upon said pins.

In testimony where I affix my signature in presence of two witnesses.

JOHN W. FRYER.
